UNITED STATES PATENT OFFICE.

PAUL J. OLSEN, OF OAKLAND, CALIFORNIA.

DESIGN FOR A COMBINATION LAMP AND LOUD SPEAKER.

Application filed December 3, 1927. Serial No. 24,377. Term of patent 3½ years.

To all whom it may concern:

Be it known that I, PAUL J. OLSEN, a citizen of the United States, and a resident of the city of Oakland, county of Alameda, State of California, have invented a new, original, and ornamental Design for a Combination Lamp and Loud Speaker, of which the following is a specification, reference being had to the accompanying drawings, forming part thereof.

The drawing is a perspective view of the combination lamp and loud speaker illustrating my new design.

I claim:

The ornamental design for a combination lamp and loud speaker substantially as shown.

PAUL J. OLSEN.
